COVERING MATERIAL

John A. Topping, Bronxville, N. Y.

Application September 1, 1933, Serial No. 687,794

6 Claims. (Cl. 164—17)

This invention relates to covering material and more particularly relates to covering material in strip form having tabs upon the edge thereof to be exposed.

5 Strips of covering material laid in overlapping arrangement have been used for roofs and for other surfaces and strips having, along the edge thereof to be exposed in the overlapping arrangement, tabs separated by spaces between the tabs have found wide use for such coverings. In 10 order to produce designs in the assembly of the strips upon the surface to be covered or to produce designs in the strips themselves, such covering strips have been made with their edges formed in outlines of ornamental character. For 15 example, strips with rectangular tabs and wide rectangular spaces therebetween or with hexagonal tabs separated by hexagonal spaces have been used. It also has been proposed for certain 20 ornamental purposes to provide a strip with a sinuous outline. Such strips may be laid upon the surface to be covered with the tabs in different courses in certain relations to each other and with 25 said tabs in certain relations to the spaces between the tabs to produce different design effects.

Particularly for this purpose have been used strips, such as those with hexagonal tabs or with 30 edges of sinuous outline, in which the tabs are of a form complementary to the spaces between the tabs. This form of strip has not only made it possible to produce pleasing design effects in the 35 assembly of the strips upon a surface but has contributed to the saving of material since such a strip may be cut from a sheet without waste along the ornamental edges thereof. This result is made possible because the tabs formed upon one portion of the sheet severed by such a cut fit into the spaces formed in the sheet upon the other portion thereof. Moreover, such a severing cut 40 in the more recent methods and apparatus for producing covering elements may be made in a continuous operation by fitting to a suitable cylindrical member in a machine producing covering elements a knife or cutting edge of the desired form so that a continuously moving sheet 45 passing under the cylinder will have the severing cut made longitudinally of the sheet to produce the complementary tabs and spaces.

While for certain purposes a simple form of 50 tab and space complementary thereto is satisfactory and may be made by the processes heretofore known as described above, in other cases it is desirable to produce variations of the mechanical form of such strips. Such modified forms may or may not have design characteris-

tics and certain designs may result from laying strips of said type upon a surface. For example, a strip having an edge of sinuous outline may be provided with notches at either side of each tab thus modifying also the form of the space between the tabs. Such designs are the subject of my design applications, Serial No. 49,184 and Serial No. 49,185, filed Sept. 1, 1933.

5 The present invention is concerned with the mechanical form of the strips with respect to 10 the relation of tabs and spaces. It is also concerned with the process of producing such modified forms of covering strips while maintaining the advantages of producing such strips in a continuous process without waste of the material in 15 forming the tabs and spaces.

According to my invention I form in a sheet a 20 severing cut of such outline as will produce upon each side thereof tabs and spaces between tabs. Within the scope of my invention these tabs and 25 spaces in the strip on one side of the severing cut may be equal in width and complementary to each other in outline or they may be unequal in widths and lengths and complementary only to the corresponding spaces and tabs on the other 30 side of the severing cut. In the preferred embodiment of my invention, however, I form on the portions on either side of the severing cut a series of tabs of a given outline, which outline is 35 complementary to the outline of the space separating the tabs. It will be thus seen that the tabs and spaces on the other side of the severing cut also will be complementary to each other and complementary respectively to the spaces and tabs on the opposite side of the severing cut. 40 While in some cases, as stated above, I may desire to produce strips with non-uniform tabs and spaces in the assembled covering structure, in general, from a commercial standpoint the formation of the tabs of equal and complementary 45 form makes possible the production of strips on either side of the severing cut which are alike and which, therefore, do not have to be handled separately but may be stacked and prepared for shipping by piling the strips produced on one side of the cut upon those produced upon the other side of the cut. As the tabs on all the strips and likewise the spaces on all the strips are alike the two strips thus produced are interchangeable.

50 The process by which, according to the present invention, I propose to make the modifications referred to above in the strips of the type described, consists of removing a portion of the sheet adjacent to and at either side of the severing cut in order to form the notches or cutouts in the tabs. 55

While it is necessary to waste a small piece of the covering material for each such cutout formed, I am thus able by a single simple operation which, as will be understood from the description to follow, may be carried out simultaneously with the formation of the severing cut, to modify the form of the tab and, as well, the form of the space between the tabs. Particularly in assemblies of covering strips, such modifications of the tabs and of the space between the tabs is effective to produce differences in design which are novel and pleasing but which may be made by the process proposed by the present application without unduly adding to the expense of manufacture. Such assembly designs are characterized by outlines which may be symmetrical but as to the outline of the parts at each side of a laterally extending axis of the design are not complementary.

20 The invention will be more clearly understood from the description taken in connection with the drawings in which

Figure 1 shows a sheet cut in hexagonal outline with notches in the outer edges of the tabs.

25 Figure 2 shows an assembly of the strips of Figure 1.

Figures 3 and 4 show an apparatus for producing the strips of the invention.

30 Figure 5 shows a sheet cut in sinuous outline to produce strips having notches in the sides of the tabs.

Figure 6 shows an assembly of the strips of Figure 5.

Figure 7 shows a cutting tool.

35 In Figure 1 a sheet of covering material is shown as indicated by the number 1. Such a sheet may be of any suitable material. For surfaces exposed to the weather such coverings are commonly made of roofing materials such as roofing felt impregnated with asphalt and having a surface coating of asphalt thereon to bind upon the covering a surfacing material such as granular slate. In carrying out the process of my invention the sheet of material may be severed into 40 two parts, for example by a cut 2 extending generally lengthwise of the sheet and so formed as to produce in each of the strips tabs 3 separated by the cut 2. In the form of strip illustrated in Figure 1 these tabs are of hexagonal shape and, 45 as may be seen from the drawings, in the particular case illustrated are of like outline and complementary to the spaces between the tabs. There are therefore produced on the strips on either side of the cut of hexagonal outline tabs 50 of like shape or form and size so that when the strip at one side of the cut is separated from that at the other side of the cut they may be placed one upon the other and the tabs as well as the spaces will be alike in the two strips. Such a set 55 of strips may be used to form a hexagonal design in the roof or a simulation of an assembly of hexagonal shingles as shown generally in Figure 2.

60 In addition to the severing cut 2 forming the general outline of the tabs and spaces, according to my invention I form the cuts or cutouts 5 which, in the particular design of strip illustrated in Figures 1 and 2, is of a circular outline. This cut 5 is made partly in one strip and partly in the other strip at each side of the severing cut 65 2. There is thus removed a piece of material 6 from the sheet 1. The removal of this piece of material forms a notch 7 in one strip and a notch 8 in the other strip. The notch 7 in the particular design illustrated in Figure 1 is made in 70 the rear edge of the recess between the tabs. The 75

notch 8 is made in the forward edge of the tab. The removal of said material from both portions of the sheet at either side of the severing cut constitutes a feature of the process of my invention by which modifications of the design produced by a simple severing cut as heretofore made may be accomplished while maintaining the advantage of a continuous cutting operation if so desired and also the advantage of obtaining strips of like form.

10 The modifying cut 5 may be made after the two strips are separated but this may require a separate operation and one which does not lend itself to the continuous process by which the severing cut 2 may be made. The cut 5 may be 15 made prior to the formation of the severing cut 2 but in such case in a continuous process it may become necessary to properly align the severing cut with respect to the position of cutouts formed by removal of the piece 6 from the sheet 1. Preferably, therefore, I form the cut 5 simultaneously with the formation of the severing cut 2. This I may do by providing the knife edge or other instrument such as a die used to sever the sheet along the outline 2 with a form providing cutting 20 edges also to cut the sheet in circular outline to form the edges 7 and 8. It is also clear that I may make the severing cut 2 and immediately 25 may punch through the sheet 1 astraddle said cut, thus removing the portion 6 of the sheet 30 and forming the edges 7 and 8. All such methods of procedure and others which may be apparent to those skilled in the art are within the scope of my invention which provides for the removal of a portion of the sheet astraddle a severing cut 35 forming the outline of two strips of covering material.

35 In general, however, I prefer to form the severing cut 2 and the cut 5 in a continuous operation by mounting upon a cylinder a cutting edge of 40 the desired outline to form the tabs and spaces therebetween, which cutting edge is suitably associated with cutting edges for producing the circular cut 5 and to remove the portion 6 of the sheet. For this purpose conveniently may be 45 used a cylinder 10 as shown in Figures 5 and 6 upon which is mounted the knife 12 of a form to produce the severing cut 2. As shown in Figures 5 and 6 the sheet 1 may be fed between said cylinder 10 and a counter roll 11 so that by rotating the cylinder 10 the knife 12 is pressed 50 against and through the sheet 1 to form the severing cut. At 15, in suitable relation to the knife 12 properly to position the circular cuts 55 with respect to the tabs so as to produce the desired design is provided the cutting edge for making the cutouts 5. This cutting edge preferably is arranged adjacent an opening 16 in the cylinder through which the cutout portions 6, 60 which are removed from the sheet, may be delivered to the cylinder chamber 17 of the cylinder. Said chamber may be provided with sloping walls so as readily to discharge said cutout portions therefrom. The cutting edge 15 in the particular embodiment illustrated, in order to form the circular cut 5 is of circular outline with the diameter of the circle upon the cutting edge 12, which forms the edge of the tab and the rear edge of the complementary space. It will be clear, therefore, that 70 as the sheet 1 is passed continuously between the cylinder 10 and the counter roll 11 not only will the severing cut 2 be made in the sheet but the pieces 6 will be cut therefrom to form the notches 7 and 8 in the two strips at either side of the cut 75

2; said operations being continuous and in proper relation to each other.

While the invention has been described above in connection with a strip having hexagonal tabs and circular notches and particularly in connection with a continuous process of producing the strips using continuously operating apparatus for carrying out the continuous process, I may produce the strips of my invention by hand or with the use of hand tools. As an illustration of this method of carrying out the process in Figure 5 is shown a sheet 1 in which a series of holes 25 of diamond shape are made in a strip along the center of the length thereof. I may first form these notches by using a tool such as a hand punch to remove the portions 26 of the base sheet 1. I may then form severing cuts 22 by using a substantially semi-circular cutting knife 30 suitably constructed, as may be seen in Figures 5 and 7, so that its edge may be pressed into the sheet 1 and so as to connect between two consecutive holes 25. Said knife may be provided with a handle 31 which also may serve as a part upon which a blow of a hammer may be struck. By properly positioning the cutting knife 30 I form the cut 22 so as to be at one side of the line of said notches or holes. I then may form a similar cut 22 on the opposite side of said line of holes and connecting the second hole with the third hole. The second cut 22 will be in reverse position to the first cut 22. By continuing these steps I may completely sever one portion of the sheet 1 at one side of the series of holes from the other portion and may produce strips which are of complementary form as to their tabs and recesses but which have notches 25 cut in the sides of the tabs. These notches 27 modify not only the form of the tab but the form of the recess between the tabs as will be apparent from the assembly shown in Figure 6. It should be noted that the notches or holes 25 are formed by complete removal of a portion of the base sheet substantially astraddle the sinuous outline which, in the embodiment shown in Figures 5 and 6 is produced by the semi-circular cutting edge used to form the cuts 22. I may, however, first form the cuts 22 and then may punch the holes 25 astraddle the outline of said cuts 22.

As shown in Figure 5 the lengthwise strips 1 of the sheet material may be subdivided by cuts 35 transversely of said strips to cut said strips into elements upon which are formed the tabs and spaces of sinuous outline. By making the transverse cut 35 with an offset 36 means is provided for aligning the strips in each course by fitting to each other the offsets of elements adjacent endwise to each other in the course. This relationship is substantially that in which they are formed in the lengthwise strip 1 as illustrated in Figure 5. Moreover, such offsets may be used for positioning the elements being laid in one course with respect to a subjacent course by superimposing said offset over the rear edge of the strip in said subjacent course. By properly positioning the offset 36 in each strip with respect to the rear edge of said strip and with respect to the tips of the tabs on said strip, the accuracy and repetition of the design formed in the assembly of strips upon the surface is insured.

Various modifications of my invention may be made to produce different designs and to suit particular conditions and the order of the steps and the types of devices which may be convenient to carry out such steps may vary in different cases. All such variations, however, are

within the scope of my invention which covers the process of producing modifications of the forms of tabs and spaces therebetween on covering strips by removing portions of the strips on either side of a severing cut made to provide the tabs and spaces. The tabs and the spaces thus become not complementary although retaining the general form of the complementary outlines with which they were made.

What I claim as new is:

1. Process of producing a covering element which comprises forming in a sheet of material a cut having an outline providing tabs with recesses therebetween, said cut being formed without removal of material to produce said recesses between the tabs, and cutting out a portion of said sheet partly on one side and partly immediately on the other side of said cut to form in the element at each side of said cut a notch in the edge of its tab, said portion being so cut with respect to said outline as to position the notches respectively in similar relation to their tabs.

2. Process of producing strips of covering having tabs along an edge thereof which comprises cutting a sheet without removal of the material thereof in an outline providing similar tabs on the parts on each side of said outline and providing spaces between the tabs complementary to said tabs, and forming in the sheet a cutout so positioned in the sheet with respect to said outline of said cut as to remove a portion of the sheet immediately at either side of said outline, said cut-out being so positioned along said outline that said portions removed from the sheet form notches in the tabs on either side thereof which are like-positioned in said tabs.

3. Process of producing strips of covering having tabs along an edge thereof which comprises cutting without removal of the material thereof an elongated sheet longitudinally thereof between its longitudinal edges in an outline providing the tabs on the two parts on each side of said cut and providing spaces therebetween complementary to said tabs, and forming in the sheet at least one cutout per tab so positioned in the sheet with respect to said longitudinal cut as to remove a portion of the sheet immediately at either side of said longitudinal cut and to make said tabs not complementary to said spaces while forming in said two parts like strips of the covering.

4. Process of producing a covering element which comprises forming in a sheet of material without removal of the material thereof a cut having a sinuous outline providing upon the parts of the sheet at either side of the cut tabs with spaces therebetween of complementary outline to that of said tabs, and cutting out a portion of the sheet partly on one side of said sinuous outline and partly immediately on the other side thereof to form notches in the two portions of said sheet at either side of said outline, said portion being cut out from the sheet at a point along said outline such that the notches formed thereby respectively are similarly positioned with respect to said outline in the two elements on either side of said cut.

5. Process of producing covering elements which comprises forming in a sheet of material a cut having an outline providing along the edge of each of the two parts of the sheet at either side of the cut recesses and tabs respectively similar in the two parts, and simultaneously removing a portion of a tab of one part at one side of said cut and a portion of the tab of the other part immediately at the other side of said cut to form notches

in said tabs, said notches being similarly positioned in said tabs.

6. Process of producing covering elements which comprises forming in a sheet of material a cut 5 having a sinuous outline providing upon the parts of the sheet at either side of the cut tabs with spaces therebetween of complementary outline to that of said tabs, and cutting out a portion of the

sheet partly on one side of said sinuous outline and partly immediately on the other side thereof to form notches in the two portions of said sheet at either side of said outline, said notches being made at a point on said outline symmetrically positioned with respect to the tips of the two tabs whereby strips with like tabs are formed.

JOHN A. TOPPING.
